UNITED STATES PATENT OFFICE

152,266

DESIGN FOR A TELEVISION RECEIVER CABINET

Albert L. Jenks, Dixon, Ill., assignor to Motorola,
Inc., Chicago, Ill., a corporation of Illinois

Application February 25, 1948, Serial No. 144,725

Term of patent 14 years

(Cl. D56—4)

To all whom it may concern:

Be it known that I, Albert L. Jenks, a citizen of the United States, residing in Dixon, in the county of Lee, State of Illinois, have invented a new, original, and ornamental Design for a Television Receiver Cabinet, of which the following is a specification, reference being had to the accompanying drawings forming a part thereof, in which:

Fig. 1 is a front perspective view of a television receiver cabinet embodying my new design; and
Fig. 2 is a side elevational view of the cabinet.

I claim:

The ornamental design for a television receiver cabinet, substantially as shown.

ALBERT L. JENKS,
